UNITED STATES PATENT OFFICE.

UMBERTO PIAGNERI, OF SAN FRANCISCO, CALIFORNIA.

COMBINATION FOUNTAIN PEN AND CIGARETTE HOLDER.

Application filed October 24, 1925. Serial No. 64,494.

This invention relates to a fountain pen, and particularly to an attachment whereby the fountain pen may also be used as a cigar or cigarette holder.

5 The object of the present invention is to generally improve and simplify the construction and operation of devices of the character described; to provide a fountain pen which may be filled with ink to allow writing when desired; to provide a cap for the pen which may also serve as a cigar or cigarette holder; to provide a mouthpiece; and, furthermore, to so construct the several parts that a central smoke passage is formed between the holder and the mouthpiece thereby permitting the device as a whole to serve as a cigar or cigarette holder when smoking.

One form which the invention may assume is exemplified in the accompanying drawings 20 and specifications in which—

Figure 1 is a central longitudinal section of the combination fountain pen and cigarette holder,

Figure 2 is a side elevation of the pen showing the cap in position,

Figure 3 is a side elevation of the pen showing the position of the cap when the device is employed for writing,

Figure 4 is a cross section on line 4—4, 25 Figure 1.

Referring to the drawings in detail, and particularly Figure 1: "A" indicates a barrel which is closed at opposite ends by the head members, shown at "B" and "C". The head member "B" carries the pen, 2, and the ends provide a passage, 3, through which the pen is fed with ink.

On the head member "C" is a threaded connection with the opposite end of the barrel 40 "A" as shown at 4 and it serves as a closure for the end of the barrel. It also serves as a mouth piece when smoking as will hereinafter be described.

The head member or mouth piece "C" is 45 provided with an inner tubular extension, 5, which is secured in the member "C" or formed integral therewith. The tube forms a continuation of a passage, 6, in the mouth piece and it is extended to enter the central passage, 7, formed in the head member, "B". The tube, 5, is provided with a shoulder for the reception of the packing gasket, 9, and this gasket serves the function of forming a leak proof joint between the tube 5 and the 55 central passage 7 when the mouth piece or member "C" is secured in the barrel "A".

An annular chamber is formed within the barrel and exterior of the tube 5 and this chamber is adapted to be filled with ink, as indicated at 10 when the head member "B" 60 is unscrewed; that is, the screw connection 11 is also formed between the head "B" and the barrel.

The pen, as a whole, is otherwise provided with a tubular cap "D" which carries an inner head or closure, 12. This closure is secured to the cap or formed integral therewith and it forms a support for the inner tube 13 which is screwed thereto. This tube is threaded at its opposite end as shown at 14 70 and the central passage 7 of the member "B" is also threaded to receive the tube.

An annular chamber 15 is formed between the tubular cap D and the inner tube 13 and this annular chamber forms a receptacle for 75 the pen 2 when the cap is applied as shown in Figures 1 and 2.

The cap serves two functions—either that of a cap or closure for the pen or that of a cigar or cigarette holder. The outer end is 80 provided with a removable reducer head, 16. The head when applied serves the function of a receiver supporting a cigarette, as indicated by dotted lines, at 17. The head when removed permits the insertion of cigars as 85 shown by dotted lines, at 18.

The operation of the device will be as follows:

With the several parts assembled as shown in Figure 1 the device serves as a cigar or cigarette holder, as it is only necessary to place a cigarette or cigar in the outer end of the cap as indicated in Figures 1 and 2, and then place the mouthpiece in the mouth, as usual. The smoke of the cigarette or cigar 90 passes through the tube 13, the passage 7, the tube 5 and the passage 6. The passage of the smoke through the device can do no injury to the pen as this is protected by the chamber 15 and contamination of the ink cannot take 95 place as this is entirely sealed with relation to the smoke passage formed through the several connecting tubes.

If it is desired to use the device as a fountain pen, it is only necessary to remove the cap 100 "D" and place it on the opposite end of the barrel or the mouthpiece "C". The pen 2 is then exposed and the device may be used as an ordinary fountain pen as the ink will be automatically fed to the pen through passage 110 3 as writing proceeds.

If it is desired to refill the fountain pen at

any time, it is only necessary to unscrew the head, "B" and hold the barrel A in a vertical position. Ink may then be dropped in the annular chamber formed between the barrel 5 and the inner tube 5 or it may be filled by means of an ordinary dropper. Leakage of the ink into the smoke passage is prevented when the head is again threaded as the gasket 9 is compressed between the inner end and the head of shoulder 8. No leakage can take place between the tube 5 and the mouth piece as a permanent connection is made or it is formed integral with the mouth piece.

While certain features of the invention are 15 more or less specifically illustrated and described, I wish it understood that changes may be resorted to within the scope of the appended claims; also, that the materials and finish of the several parts employed may be 20 changed to suit varying conditions and to produce ornamental effects.

Having thus described my invention, what I claim and desire to secure by Letters Patent is—

25 1. An article of manufacture comprising a barrel having an ink containing chamber formed therein; a head member on each end of the barrel and forming closures for the ink chamber; one head adapted to carry a pen; a mouth piece on the opposite head; means whereby a cigarette may be supported with relation to the first named head and means whereby smoke is conveyed from the cigarette supporting means to the mouth 30 piece.

35 2. An article of manufacture comprising a barrel having an ink containing chamber formed therein; a head member on each end of the barrel and forming closures for the ink chamber; one head adapted to carry a pen; a mouth piece on the opposite head; means whereby a cigarette may be supported with relation to the first named head and means whereby smoke is conveyed from the cigarette supporting means through the heads 40 and the barrel to the mouth piece.

45 3. An article of manufacture comprising a barrel having an ink containing chamber formed therein; a head member on each end

of the barrel and forming closures for the ink 50 chamber; one head adapted to carry a pen; a mouth piece on the opposite head; a combination cap and cigarette holder adapted to be attached to the first named head and means whereby smoke is conveyed through 55 the cap, the heads and the barrel to the mouth piece.

4. An article of manufacture comprising a barrel having an ink containing chamber formed therein; a head member on each end 60 of the barrel and forming closures for the ink chamber; one head adapted to carry a pen; a mouth piece on the opposite head; a combination cap and cigarette holder adapted 65 to be attached to the first named head; and a tubular connection formed between the cap and the mouth piece and extending through the cap, the heads and the barrel.

5. An article of manufacture comprising a barrel having an ink containing chamber 70 formed therein; a head member on each end of the barrel and forming closures for the ink chamber; one head adapted to carry a pen; a mouth piece on the opposite head; a combination cap and cigarette holder adapted 75 to be attached to the first named head and a tubular connection formed between the cap and the mouth piece and extending through the cap, the heads and the barrel, said first named head having an interlocking connection with the said tubular connection for permitting the removal of the first named head 80 to fill the ink chamber.

6. An article of manufacture comprising an elongated tube, a mouthpiece secured on one end thereof, a pen head secured on the opposite end of the tube, a barrel surrounding the tube, said barrel being secured at its opposite end to the pen head and to the mouthpiece and forming an annular ink containing chamber, said pen head adapted to carry a pen, a cap carried by the pen head for enclosing the pen, a cigarette holder in the outer end of said cap, and a tube carried by the cigarette holder and adapted to form 90 communication between the cigarette holder and the first named tube.

UMBERTO PIAGNERI.
